UNITED STATES PATENT OFFICE.

JESSE EMMERT, OF REYNOLDS, NEBRASKA.

BED SPRING-BOTTOM.

SPECIFICATION forming part of Letters Patent No. 364,233, dated June 7, 1887

Application filed February 7, 1887. Serial No. 226,759. (No model.)

To all whom it may concern:

Be it known that I, JESSE EMMERT, a citizen of the United States, residing at Reynolds, in the county of Jefferson and State of Nebraska, have invented certain new and useful Improvements in Bed Spring-Bottoms; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to bed spring-bottoms, and has for its object the construction of a spring-bottom having only one end—the head—secured to the frame, and which will gradually grow more yielding from said end to the opposite or foot end.

The improvement consists in having a series of transverse bars supported upon the ends of inclined springs or spring-arms and in having the transverse bars connected together in any desired manner.

The improvement further consists in the novel features more fully hereinafter set forth, claimed, and shown in the drawings, in which—

Figure 1 is a perspective view of a bed-bottom embodying my invention. Fig. 2 is a side view showing by dotted lines the position of the bottom depressed by the weight when placed near the head. Fig. 3 is a view similar to Fig. 2, showing the weight placed nearer the foot.

The bed-bottom is composed of the base and the spring-top. The base comprises the series of slots A, united at the foot by the cross-bar a and at the head by the bar B, which is braced at each end by the blocks b, set in the angle formed between it and the side slats. The transverse bars C, supported upon the ends of the inclined springs or spring-arms d, are suitably connected together by the wire fabric D, although any other fabric or connection will answer the same purpose equally as well. The spring-arms incline toward the head and have their lower ends fastened in the base. There may be as many of these spring-arms for each transverse bar as found necessary, one for each slat being sufficient. They are composed of stout spring-wire, having a coil, d', formed near their lower ends and the

arms d² projected forward from such coils and adapted to rest upon the base and have their ends d³ bent downward and let into said base 55 for holding them in position. The staples d⁴, driven over the arms d², near the coils d', into the base, serve, in addition to the ends d³, to further hold the arms or springs in place. The transverse bar at the foot is supported by the 60 spring-extensions e of the rear or foot springs. These extensions form an integral part of the foot-springs, and are parallel with the base or arms. The head end of the fabric or connection D is connected with the head-board B. 65

A weight placed upon the fabric D near the head will have to overcome the combined resistance of all the springs; consequently will not depress the bottom to any great degree. The same weight placed at a greater distance 70 from the head and in the rear of the first series of springs will have a tendency to act on those springs in the rear of the first set of springs and will depress that portion of the bed to a greater extent, and so on for any 75 other position of the weight as the same is moved nearer the bottom.

The greatest weight of a person is near the head and the least at the foot; hence a person resting upon a bed-bottom of my construction 80 will have the greatest support at the head and the least at the foot; hence the weight of the person will be equalized and great comfort will be experienced, as the spring-bottom will yield equally proportionately to the weight. 85

I am aware that it is common to construct a bed-bottom of springs which are arranged so that one portion inclines in one direction and the other portion inclines in an opposite direction, and also that said springs are connected to the side rails and head and foot of the bed, and I lay no claim, broadly, to such construction and arrangement.

Having thus described my invention, what I claim, and desire to secure by Letters Patent, 95 is—

1. The combination, with the base and the series of independent springs projected upward therefrom and inclined toward the head of the base only, of the transverse bars supported by the free ends of said springs and connected together and to the head of the base only, whereby the springs exert a combined force near the head, which force diminishes 100

toward the foot, substantially as and for the purpose set forth.

2. The herein shown and described bed-bottom, consisting of the combination of the base, the inclined springs arranged in series, the horizontal extensions projected rearwardly from the last springs of the series, the transverse bars carried by the free ends of the springs and at each end of the extensions, and to the top connecting said bars to each other, and

connected with the head of the base only, substantially as described, and for the purpose specified.

In testimony whereof I affix my signature in presence of two witnesses.

JESSE EMMERT.
